CHARLES F. DILKS, OF BRIDGETON, NEW JERSEY, ASSIGNOR OF ONE-HALF TO ISIDORE W. GOLDBERG, OF BRIDGETON, NEW JERSEY.

NEEDLE FOR TALKING-MACHINES.

1,317,671.

Specification of Letters Patent. Patented Sept. 30, 1919.

Application filed November 30, 1918. Serial No. 264,799.

To all whom it may concern:

Be it known that I, CHARLES F. DILKS, a citizen of the United States, residing in Bridgeton, Cumberland county, New Jersey, 5 have invented certain Improvements in Needles for Talking-Machines, of which the following is a specification.

My invention relates to needles or styli for sound-reproducing machines; and the 10 object of my invention is to provide a scratchless metal needle. Various attempts have been made to produce needles of this character, but without success so far as any practical marketable article is concerned. 15 In my improved construction, however, I have produced a needle which, when employed with disk records, produces a soft, mellow sound; avoiding the scratchy sound common with needles heretofore employed 20 with records of this character. My improved needle comprises a stem, a point or pointed end, with a springy or flexible connection between said parts, and a supplemental spring strip or finger.

25 These and other features of my invention are more fully described hereinafter, reference being had to the accompanying drawings, in which:

Figure 1, is a side elevation of a sound 30 reproducer of any usual construction showing one form of needle embodying my invention employed therewith.

Fig. 2, is a perspective view, on a larger scale, of the form of my improved needle 35 shown in Fig. 1.

Fig. 3, is a side elevation of the point end of the needle shown in Figs. 1 and 2, illustrating one manner of attaching the springy or flexible members thereto, and 40 Figs. 4 and 5, are views similar to Fig. 3, illustrating modified constructions within the scope of my invention.

My improved needle, made of metal, may 45 comprise a stem portion 1 adapted for insertion in the usual socket 2 of the reproducer, in which it may be retained by an ordinary set screw 3 in the usual manner. This needle is provided with a point portion 4, which may comprise a body 4^a and 50 a point proper, indicated at 4^b, which may be and preferably is of the permanent type, and these two parts 1 and 4 are connected together by a flexible strip or section 5 of spring metal of high tension and of relatively thin gage. While the flexible sec-

tion 5 may be connected to the stem 1 and the point portion 4 in any suitable manner, I have shown these parts slotted or notched, at 1^a and 4^c, respectively, to receive the ends of the same. It is obvious that other means 60 of mounting said spring section 5 with respect to the stem 1 and point portion 4 may be employed; all of which is within the scope of my invention.

Connected to the point portion 4, or to the 65 spring section 5, is a supplemental spring strip or finger 6, which may be shaped substantially as indicated in the drawings, and the upper end of this supplemental spring 6 lies in engagement with the socket 2 when 70 the needle is employed with the reproducer and in engagement with a record, as clearly indicated in Fig. 1.

The needle is truly flexible, and does not 75 partake of the vibrations of the socket due to usual causes, since such vibrations are immediately taken up by the main spring section 5 and the supplemental spring strip or finger 6, with the result that a softer tone is reproduced without the scratchiness 80 common in the employment of metal needles with the disk records of talking machines.

In the structure shown in Figs. 1, 2 and 3, both spring members 5 and 6, are illustrated as being secured in the slot or notch 85 4^c of the point portion 4. In lieu of this, the supplemental spring member 6 may be integral with the spring member 5 as indicated in Fig. 4, or it may be connected to the spring member 5 by a rivet 7 or other 90 fastening means, as indicated in Fig. 5.

While I have shown my improved needle as having a point portion to which the spring section 5 is connected, it is obvious 95 that a needle in which the point for engagement with the groove of the record is integral with said spring section is within the scope of my invention, and my claims, in their broader aspect, are to be so construed. In all instances the point which 100 engages the groove of the record is preferably of the permanent type.

While I have shown the stem portion 1 as round, it is obvious that it may be of any suitable shape, and also that it may be of a 105 special shape to be received within a socket of special shape so that when inserted in said socket the flexible or spring connection 5 and the supplemental spring 6 will be disposed in the proper position with re- 110

spect to the record engaged by the needle point; such position being illustrated in Figs. 1 and 2.

I claim:

- 5 1. A needle for talking machines, comprising a spring stem and a groove-engaging point, and a supplemental spring carried by said needle for engagement with its support.
- 10 2. A needle for talking machines, comprising a stem of flat spring metal, a groove-engaging point, and a supplemental spring

carried by said needle for engagement with its support.

3. The combination, in a needle or stylus 15 for sound-reproducing machines, of a socket-receiving stem, a point, a section of spring metal connecting said members, and a supplemental spring disposed at the side of said stem section and connected at one 20 end only to the needle, said supplemental spring contacting with the needle support when the needle is in use.

CHARLES F. DILKS.
